UNITED STATES PATENT OFFICE.

GEORGE W. PENTHENY, OF SPRINGFIELD, AND VYACHESLAV PETROVSKY, OF LYNN,
MASSACHUSETTS, ASSIGNORS TO GENERAL ELECTRIC COMPANY, A CORPORATION
OF NEW YORK.

ELASTIC-FLUID TURBINE.

1,366,592.

Specification of Letters Patent. Patented Jan. 25, 1921.

Application filed August 2, 1919. Serial No. 314,997.

To all whom it may concern:

Be it known that we, GEORGE W. PENTHENY, a citizen of the United States, residing at Springfield, county of Hampden, State of Massachusetts, and VYACHESLAV PETROVSKY, a citizen of the United States, residing at Lynn, county of Essex, State of Massachusetts, have invented certain new and useful Improvements in Elastic-Fluid Turbines, of which the following is a specification.

The present invention relates to elastic-fluid turbines and specifically to the construction of the rotor and the means for attaching buckets or blades thereto and has for its object to improve their construction.

For a consideration of what we believe to be novel and our invention, attention is directed to the accompanying description and claims appended thereto.

In the drawing which is illustrative of our invention, Figure 1 is a partial axial section of a bladed rotor and Fig. 2 is a partial view in elevation of the same.

3 indicates the main body of a rotor having the usual web 4 which is connected to the supporting shaft. The rim of the rotor is somewhat enlarged to furnish the necessary support for the blades 5. The rim is provided with a plurality of concentric shoulders 6, said shoulders having relatively large, flat concentric bearing surfaces 7. As shown the faces of said shoulders all terminate in the same vertical plane but this is not essential. The rim is beveled off at 8 to permit it to enter a recess in the blade bases as will appear later. The rim is also provided with an annular undercut recess 9 and an annular retaining shoulder 10. The lower ends of the blades extend into this recess and are held by a calking strip 11. By preference the inner end of the blade base is beveled at its inner end and oppositely to the side wall of the recess so that the calking strip when finally forced into place is tapered on both sides, a feature which aids in holding it in place against centrifugal stresses.

The blades 5 are formed individually as by the drop forging process for example, or they may be cut out of solid stock. However they are made, each blade has a base 12 formed integral therewith which also forms a space block to properly separate the working surfaces of the blades. Each base is provided with a plurality of concentric shoul-

ders 13 which are the counterparts of the shoulders on the rim and when assembled are in firm contact. The shoulders on both the blades and rotor are surfaces of revolution and the finishing cuts may advantageously be made with special tools designed for the purpose, to insure accuracy. One side of the base is beveled off at 14 to permit it to enter the recess 9 in the rim. The opposite side is provided with a recess 15 and a shoulder 16. Located in the recess between the shoulder and the rim is a calking strip 17. The calking strips 11 and 17 are made in sections of suitable length and are forced into place by a suitable calking tool. Each calking strip may cover an arc equal to one blade or it may cover two or more blades as desired.

The blades with their bases are finished individually and are mounted on the rim one after the other, the recesses 9 and 15 permitting this to be done from one side of the rotor, after which they are locked in place by the calking strips. The blades can be removed by taking out the calking strips, a feature which is desirable for repair purposes.

The concentric shoulders on the rotor and blade bases afford a firm means for anchoring the blades against centrifugal force. The overlapping of the shouldered portions of the bases and rim together with the calking strips 11 and 17 located on opposite sides of the rotor and at different radial distances from the rotor axis afford an effective means for resisting strains due to the action of the steam on the blades.

In accordance with the provisions of the patent statutes, we have described the principle of operation of our invention, together with the apparatus which we now consider to represent the best embodiment thereof; but we desire to have it understood that the apparatus shown is only illustrative, and that the invention can be carried out by other means.

What we claim as new and desire to secure by Letters Patent of the United States, is,—

1. In combination, a turbine member having a plurality of concentrically arranged projections on one only of the side faces of its peripheral portion, the other side face being smooth, blades provided with bases which have similar projections on one side

only, said projections interlocking with those on the member and retained thereby, and a means on opposite sides of the member for locking the blades in place.

5 2. In combination, a turbine rotor having a rim with a shoulder on one of the side faces thereof, blades, each of which has a base provided with a shoulder on one of its side faces which engages that on the rotor, 10 and means on opposite sides of the rotor and at different radial distances from the rotor axis for holding said shoulders in engagement and resisting lateral stresses on the blades when they are subjected to the 15 action of motive fluid.

3. In combination, a turbine rotor having a rim with a shoulder on the side thereof, blades, each of which has a base provided with a shoulder on one side which engages 20 that on the rotor, and calking strips located on opposite sides of the rotor and at different radial distances from the rotor axis for holding said shoulders in mutual engagement and resisting lateral stresses on 25 the blades when they are subjected to the action of motive fluid.

4. In combination, a turbine rotor having

a rim with a shoulder on its side face and also a circumferential recess to receive the inner ends of the blade bases, blades, each 30 of which has a shoulder on its base coöperating with that on the rotor and also a recess to receive the periphery of the rotor, and retaining devices located in said recesses for holding the blade against lateral 35 displacement.

5. In combination, a turbine rotor having a tapered rim portion with a plurality of concentric shoulders on one of its side faces, 40 blades, each of which has a tapered base portion with shoulders which coöperate with those on the rotor, and means located adjacent the ends of said tapered portions and at different radial distances from the rotor axis for holding the shoulders in mutual 45 engagement.

In witness whereof, GEORGE W. PENTHENY has hereunto set his hand this twenty-eighth day of July, 1919, and VYACHESLAV PETROVSKY has hereunto set his 50 hand this thirty-first day of July, 1919.

GEORGE W. PENTHENY.
VYACHESLAV PETROVSKY.
